ALBERT J. CICHON Inventor

Richard B. Oliver Attorney

UNITED STATES PATENT OFFICE.

ALBERT J. CICHON, OF SAN ANTONIO, TEXAS.

FILING FIXTURE.

Application filed April 7, 1925. Serial No. 21,416.

This invention relates to improvements in filing fixtures particularly adaptable for use in connection with watch makers' lathes.

An important object of the invention is to provide a fixture of the above mentioned character which will permit the accurate and smooth filing of shoulders on watch stems.

A still further object of the invention is the provision of a device of the above mentioned character which will permit the filing of watch stems and other comparatively small parts with great accuracy and speed.

A still further object of the invention is to provide a filing fixture which is comparatively simple in construction, durable, accurate and efficient for the purpose intended.

Other objects and advantages of this invention will be apparent during the course 20 of the following description.

In the accompanying drawings forming a part of this specification and in which like numerals are employed to designate like parts throughout the same:

25 Figure 1 is a side elevation of my improved device showing the same mounted in association with a lathe,

Figure 2 is a transverse sectional view taken on the line 2—2 of Figure 1,

30 Figure 3 is a horizontal sectional view taken on the line 3—3 of Figure 2,

Figure 4 is a top plan view of my device,

Figure 5 is a vertical sectional view taken on the line 5—5 of Figure 2,

35 Figure 6 is a front elevation with a portion of the device removed,

Figure 7 is a perspective view of an adjustable guide strip,

Figure 8 is a front elevation of the adjustable plate member,

Figure 9 is a perspective view of a key to be used in connection with the device,

Figure 10 is an end elevation of the adjustable plate,

40 Figure 11 is a vertical sectional view taken on the line 11—11 of Figure 6,

Figure 12 is a side elevation of a spindle which may be employed in connection with my device.

45 Figure 13 is a rear elevation taken on the line 13—13 of Figure 1, and

Figure 14 is a detailed elevation of a

chuck which may be employed to connect my device upon the lathe.

In the drawings, wherein for the purpose of illustration is shown the preferred embodiment of my invention, the numeral 15 generally indicates the frame of a lathe preferably of the type known as a speed lathe having usual tail stock 16 and head stock 17. The tail stock 16 carries a horizontal shaft 18 provided with a central bore for the reception of a supporting element.

My invention relates more specifically to an attachment to be mounted on the shaft 18 for filing such watch stems, or the like. This fixture comprises a supporting plate 19 having a comparatively wide recess 20 formed in the rear face thereof, one wall of the groove being preferably undercut at an angle to provide a guide groove. The opposite wall is grooved to receive an adjustable guide strip 21, inner of which is beveled to conform to the inclined wall of the first mentioned groove and form a retaining guide. The lower end of the body plate 19 is recessed in the central portion as at 22, for the reception of the head of an adjusting screw which will be more fully described as the description progresses.

A plate 23 is mounted to slide vertically within the recess 20, the vertical edges thereof being beveled as at 24 to engage the inclined sides of the groove and guide strip. An opening 25 is formed through the plate 23 adjacent the upper end while the central portion of the lower edge is recessed as at 26, for a purpose to be hereinafter more fully described. A vertically extending threaded bore 27 is formed in substantially the central portion of the plate 23 and, at its lower end, opens into the recess 26, this bore being adapted to receive an adjusting screw 28. The lower extremity of the adjusting screw 28 is journaled in a transverse bearing strip 29 secured to the lower edge of the plate 19 and may be adjusted by means of a head 30 the peripheral edge of which is knurled. It is obvious that by rotation of the screw the plate 19 may be vertically adjusted with relation to the plate 23.

The outer face of the plate 23 is provided, adjacent one of the beveled edges thereof, with graduations 31 indicating millimeters

or other desired measurement and adapted to correspond with similar graduations 32 formed upon the beveled edge of a gauge plate 33. This gauge plate is secured to one 5 of the side extensions of the body or supporting plate 19 by a machine screw or in any desirable manner. The front face of the plate 19 carries a pair of angular supporting brackets 34 secured to the body by means 10 of screws 35 and provided at the outermost extremities with apertured extensions forming bearings 36. These brackets are adapted to rotatably support a pair of rollers 37 provided with reduced extremities for engaging 15 the bearings 36 and suitable bearing seats formed in the body. It is to be noted that these rollers are spaced above the bracket to prevent contact therewith and permit movement of a file or similar tool upon the upper 20 sides thereof.

The device is retained in association with the tail stock of the lathe by means of a stem 38 which comprises a substantially conical head 39 and a tapered shank 40. The outer 25 face of the head 39 is provided with a cylindrical boss 41 located at the center thereof and adapted to engage a suitable recess formed in the rear face of the plate 23, the plate 23 being secured to the head 39 of the stem by means of a screw 42 fitted through 30 the aperture 25 in the plate and threaded into a bore formed in the stem. A projecting stud 43 is formed adjacent the lower portion of the taper base 39 and is adapted to engage a suitable aperture 44 formed in the plate 23 immediately beneath the opening 25 thus preventing displacement of the stem and the plate. The shank 40 of the stem is fitted 35 into a suitable bore formed in the tail stock 40 shaft 18 and is held against displacement by a pin 45 adapted to extend through registering openings in the tail stock shaft and shank 40. In some instances it may be desirable to connect the device with the lathe 45 tail stock by means of a spindle 46 having a head of construction similar to the head 39, the spindle being of comparatively large diameter and cylindrical for connection with the tail stock. I also contemplate the use 50 of a spindle 47 clearly shown in Figure 14 for the connection of the device to the tail stock, the spindle comprising, in this instance, a somewhat shorter body provided with a reduced threaded extension 48 for 55 connection with the tail stock.

It will be noted that the plate 19 is adjustable relative to the plate 23 and in order to insure accuracy in the relative movement of these plates I have provided the adjustable guide strip 21. This strip is positioned 60 between one of the beveled edges of the plate 23 and the body groove and may be adjusted horizontally by a pair of adjusting screws 49 threadedly mounted through the sides of the

body and adapted to contact with the guide 65 strip.

In use, my improved fixture may be readily mounted upon the conventional types of lathes, usually employed in the manufacture or repair of jewelry. While the device is particularly intended for jewelry work and operations of this character it is by no means restricted to this particular use and may be advantageously employed in connection with numerous types of machines 70 for filing and repair work. After the fixture has been securely fastened to the lathe tail stock, the work is secured in the head stock and the device adjusted to the pre-determined measurement. If the work consists in the filing of a watch stem, shown 75 for example in Figure 1, the plate 19 is suitably adjusted relative to the plate 23 by operation of the screw 28, the related graduations upon the adjusting plate and gauge 80 plate indicating the proper position of the fixture. The watch stem is then properly positioned by adjustment of the tail stock 85 16 and a suitable file moved horizontally over the rollers 37, this operation continuing 90 until the material upon the stem has been reduced to the proper dimension. The device is capable of employment for numerous additional operations such as filing 95 shoulders and projections.

It is to be understood that the form of my invention herewith shown and described is to be taken as the preferred example of the same and that various changes as to the shape, size and arrangement of parts may 100 be resorted to without departing from the spirit of the invention or the scope of the subjoined claims.

Having thus described my invention, I 105 claim:

1. A file supporting attachment for lathes comprising a supporting member, means carried by the member for attachment to the tail stock of the lathe and arranged to support the said supporting member in vertical position and in a plane at right angles to the axis of the tail stock, a plate mounted upon the said supporting member for vertical adjustment thereon, a screw vertically mounted upon the plate and having threaded engagement with the supporting member whereby to effect vertical adjustment of the plate in the rotative adjustment of the screw, brackets extending forwardly in spaced relation to each other from the face of the plate, and rollers rotatably mounted in horizontal position at the upper sides of the brackets to support a file.

2. A file supporting attachment for lathes comprising a supporting member, means for mounting the member upon the tail stock of a lathe, the said member comprising a plate having beveled vertical edges, a

plate disposed against the supporting plate for vertical adjustment with respect thereto and having a recess accommodating the said supporting plate, the walls of the recess being undercut, one of the said walls having a bevel to fit the corresponding vertical edge of the supporting plate, a guide strip within the other undercut wall of the recess coacting with the other vertical edge

of the supporting plate, means for adjusting the guide strip, means for vertically adjusting the second mentioned plate, and horizontally disposed, spaced rollers mounted upon the face of the said second mentioned plate to support a file.

In testimony whereof I affix my signature.

ALBERT J. CICHON.
